CN ZL200420112579.2 11/2004
TW M270809 10/1993*Primary Examiner* — John Windmuller*Assistant Examiner* — Steven Czyz(74) *Attorney, Agent, or Firm* — Philip H. Burrus, IV(57) **CLAIM**

The ornamental design for a crutch tip, as shown and described.

DESCRIPTION

FIG. 1 is a right elevation view of a crutch tip showing our new design;

FIG. 2 is a left elevation view thereof;

FIG. 3 is a front elevation view thereof;

FIG. 4 is a rear elevation view thereof;

FIG. 5 is a bottom plan view thereof;

FIG. 6 is a top, right, front perspective view thereof;

FIG. 7 is a bottom, left, rear perspective view thereof;

FIG. 8 is a bottom, left, front perspective view thereof;

FIG. 9 is another bottom, left, rear perspective view thereof;

FIG. 10 is another bottom, left, rear perspective view thereof; and,

FIG. 11 is yet another bottom, left, rear perspective view thereof.

The broken lines depict portions of the article that form no part of the claimed design.
